COUNTER

Harvey L. Spaunburg, West Hartford, Conn., assignor to Veeder-Root Incorporated, Hartford, Conn., a corporation

Application November 29, 1939, Serial No. 306,607

13 Claims. (Cl. 235—144)

This invention relates to counters and more particularly to a counter having a plurality of counting units; both of said units being adapted to indicate a counting operation, but so arranged that as one is operated in a counting direction the other is simultaneously reset to zero. As an example of use to which the counter may be applied, reference may be had to the usual dispensing units now utilized for the dispensing of gasoline. In such units it is customary to have a counting unit to indicate either the quantity or the cost of the quantity being dispensed; it being necessary at the conclusion of the dispensing operation to reset the unit to zero, and if such resetting is overlooked, the second dispensing operation will merely be added to the first.

An aim of the present invention is to provide a counter for the above-indicated or other like purposes wherein a plurality of counting units are utilized and so interconnected that upon the start of a counting operation on one unit the other unit will be automatically reset to zero.

A still further aim is to provide such a counting unit including means for automatically and simultaneously reversing the drive and resetting operation of the counting units.

A still further aim is to provide an improved, simplified, and inexpensive counting unit for the above-indicated purpose, which is positive in its action, requires a relatively small number of parts, thus making it economical to manufacture, and which may be adapted for a plurality of uses other than that indicated.

Other objects will be in part obvious and in part pointed out more in detail hereinafter.

The invention accordingly consists in the features of construction, combination of elements, and arrangement of parts which will be exemplified in the construction hereinafter set forth and the scope of the application of which will be indicated in the appended claims.

In the accompanying drawings:

Figure 1 is a view of a counter embodying the invention herein as utilized in conjunction with a liquid dispensing device; the dispenser casing being in section;

Fig. 2 is a sectional view through the counter to illustrate the means for connecting the counting units to the drive means;

Fig. 3 is an enlarged end view illustrating the means for alternately shifting the counting unit drive and reset connections;

Fig. 4 is a plan view of Fig. 3;

Fig. 5 is an end view of Fig. 3 with the operating lever thereof removed;

Fig. 6 is an end view showing the means for connecting the reset shaft to the drive shaft;

Fig. 7 is a front view partly in section of Fig. 6; and

Fig. 8 and 9 are detail views of the transfer and resetting means of the order wheels of the counting units.

Referring to the drawings, the counter A embodying the invention herein is for the purposes of illustration shown as the cost indicator of a liquid dispenser B. The liquid dispenser B is the type generally used for dispensing gasoline and comprises a rectangular casing 10 enclosing a motor 12 operatively connected through a belt 14 to a suction pump 16; the pump having its inlet connected to the usual storage tank (not shown) and its discharge to a fluid measuring meter 17.

The outlet of the meter 17 connects to a flexible dispensing hose 18 provided at its free end with a nozzle 20 having a manually operable flow valve therein. The nozzle 20 utilized herein differs from the general construction in that the heel 23 thereof is bifurcated and transversely arranged and secured between the branches thereof is a nozzle supporting pin 22. The pin 22 serves to removably support the nozzle on spaced apart hooks 24 of a supporting bracket 26 secured to the side of the casing. The bracket 26 is so supported that the hooks 24 are spaced to each side of a slot 27 provided in the side wall of the casing and through which a control member for the counter A extends for cooperative engagement with the pin 22 of the dispensing nozzle, for reasons hereinafter more fully described.

More specifically, the counter A includes a drive shaft 30 and a reset shaft 32 arranged in vertical alignment and journaled in a pair of spaced apart end brackets 34 and 36 supported on a horizontally arranged plate 38 secured in the casing 10. The shafts 30 and 32 are of equal length and substantially longer than the distance between the supporting end brackets whereby the ends of the shafts extend through and beyond same. The extending ends are joined by a pair of interconnecting links 40 and 42 having journaled ends 44 allowing the shafts to be freely rotated therein. The links are positioned and secured against longitudinal movement on the shafts by spaced apart collars 46 pinned to the shafts to each side of the link end journals 44.

With this construction, the drive shaft 30 and reset shaft 32 and the connecting links 40 and 42 constitute a frame or yoke 43 capable of being shifted laterally as a unit, but wherein

each shaft is freely rotatable within the links and independently of one another. This shifting is utilized to operate means for simultaneously and alternately reversing the counting and resetting operation of a pair of counting units 48 and 50 mounted on the reset shaft 32.

Each counting unit is shown herein as comprising three order wheels; those of the counting unit 48 being designated as 48a, 48b, and 48c, and those of the counting unit 50 being designated as 50a, 50b, and 50c; the wheels of the units being alternately arranged on the reset shaft. As indicated, the peripheral surface of each unit wheel has indicia thereon from "0" to "9", and the speed of rotation is such that the unit being operated in a counting direction will indicate the cost of the quantity of liquid being dispensed.

The rotation of the drive shaft 30 for operating the counting units is derived from a bevel gear 52 operatively connected in any suitable way to the measuring meter 17. The bevel gear 52 meshes with a bevel gear 54 splined on the drive shaft 30 by a key 56 integral with the hub thereof and freely slidable in an elongated shaft keyway 58. Gear 54 is positioned longitudinally of the drive shaft 30 by an intermediate frame member 60 and a bracket 62 secured to the frame 60, and is thus maintained in constant meshing engagement with the gear 52 when the drive shaft 30 is shifted laterally in its supporting frame.

The rotation of shaft 30 is transferred to the counting units by providing thereon for simultaneous rotation therewith a double face clutch member 64 adapted upon lateral shifting of the drive shaft to alternately engage the clutch face 66 of a transfer gear 68 or the clutch face 70 of a transfer gear 72. The transfer gears 68 and 72 are mounted for free rotation on drive shaft 30 and are maintained in proper spaced apart position by the end bracket 34, intermediate bracket 60, and a spacing sleeve 74. With the transfer gears 68 and 72 so positioned, the former is in permanent mesh with a drive gear 76 adapted when rotated to operate the lowest order wheel 48a of the counter 48 in a counting direction; whereas the gear 72 is in permanent mesh with a drive gear 78 adapted when rotated to operate the lowest order wheel 50a of the counting unit 50; the parts being so positioned in the embodiment illustrated that rotation of shaft 30 will operate counting unit 48.

As best seen in Fig. 2, the drive gear 76 is rotatably mounted on the hub 80 of the lowest order wheel 48a, and the drive gear 76 has secured to the inner face thereof for simultaneous rotation therewith a ratchet 82. Arranged to cooperatively engage the ratchet 82 are a plurality of drive pawls 84 pivoted on the adjacent ends of transverse arms 86 spaced radially from and integrally connected to the hub 80 by a spider 88. Each drive pawl 84 is maintained in engagement with the ratchet 82 by a leaf spring 90; the spring having its free end seated in a pawl notch 92 (see Fig. 8) and its fixed end held between stamped out end portions 94 of a face plate 96 secured to the arms 86 inwardly of the pawls. As is apparent, the leaf spring tends to normally pivot the pawl in a clockwise direction, and thus upon rotation of the drive wheel 76 in a counterclockwise direction the pawls 84 will latch the unit wheel thereto and cause simultaneous rotation therewith in a counting direction.

In order to progress the count from the lowest order wheel 48a to the next higher order wheel 48b, there is secured to the face of the wheel 48a adjacent the next highest order wheel 5 a locking disk 98 having offset therefrom a mutilated drive gear 100 comprising two teeth with a notch therebetween. Associated with the locking disk and mutilated gear and positioned between the wheels 48a and 48b is a transfer member 102 rotatably mounted on a shaft 104 supported by the intermediate bracket 60 and end bracket 36. The transfer member includes the usual transfer pinion 106 having alternate long and short teeth 108 and 110, all of which mesh with the mutilated gear 100 and the long teeth cooperating with the locking disk to prevent rotation of the transfer member 102 except when rotated by the mutilated gear 100.

Inasmuch as the transfer must span an intermediate wheel of the counting unit 50, the transfer member also includes a second gear 114 spaced from the pinion 106 by an elongated hub 112; the gear 114 having the same number of teeth as the pinion 106 and in constant mesh with the drive gear 116 of the next highest order wheel 48b. Thus when the lowest order wheel 48a is rotated through one complete revolution, the mutilated gear 100 will advance the transfer member 102 one step in a forward direction and advance the next highest order wheel 48b one step in a forward direction, progressing the count registering on the counter unit.

In like manner, the rotation of the counter wheel 48b is transferred to the counter wheel 48c, and as the means for accomplishing this is identical to that previously described, no further reference need be made thereto. Furthermore, as the operation of the counting unit 50 and the transfer means from one order wheel thereof to the next is identical to that of the counter 48, it will not be further described, except to point out that the transfer members 118 between each successive pair of order wheels is rotatably mounted on a shaft 120 extending between the end brackets 34 and 36 and positioned in vertical alignment with the transfer member supporting shaft 104.

From the foregoing, it becomes apparent that upon successive lateral shifting of the drive shaft 30 the double faced clutch 64 will alternately connect with one or the other of the transfer gears 68 and 72 and thus operate the counting unit with which it is connected for a counting operation. Upon such shifting, means are also provided for simultaneously causing a resetting operation of the other counting unit. This means comprises a second clutching device, generally designated as 122, for transferring rotation of drive shaft 30 to the reset shaft 32, until the reset shaft has been rotated through one complete revolution, whereupon the clutch device is automatically disengaged.

To accomplish this, there is mounted on the drive shaft 30 and keyed thereto for simultaneous rotation therewith a ratchet 124, and positioned adjacent the ratchet 124 is a freely rotatable transfer wheel 126; the latter being longitudinally positioned on the shaft between the ratchet and the adjacent link positioning collar 46. The transfer gear 126 is in constant mesh with a drive gear 128 pinned to the reset shaft 32, whereby rotation of the latter will cause a reset operation of the reset shaft.

In order to transfer the rotation of the shaft 30 to the gear 126, the gear has pivotally mounted

on a stud 130 carried thereby a kick-out pawl 132. As best seen in Fig. 6, the pawl has a downwardly extending arm 134 terminating in a tooth 136 adapted to be engaged behind a tooth of the ratchet 124 and normally urged to such engagement by a spring 138, and, when so engaged, the ratchet and transfer gear 126 rotate as a unit.

In order to break the connection at the completion of one revolution of the drive shaft, the pawl 132 is also provided with an upwardly extending arm 140 adapted to engage an associated tripping lever 142, when in position to reset counting unit 48, or a tripping lever 144, when in position to reset counting unit 50. The levers 142 and 144 depend from a stud 146 extending outwardly from the side brackets 36, and the levers are normally pivoted into forward position against a stop 148 by suitable spring means 150. When in their forwardmost position, the forward faces of the studs will lie approximately five degrees forward of the position of the pivot carrying stud 130 at the start of a revolution, and when in this position the upper end of the pawl arm 132 will lie rearwardly of the stud, and, when so positioned, the ratchet and transfer gear 126 are connected as a unit. Upon rotation of the shaft 30, the ratchet and gear will rotate through three hundred and fifty-five degrees, whereupon the upper arm 140 of the pawl will contact the forward face of the tripping lever 142, and, upon completing the revolution, the pawl will pivot the tripping lever 142 until the latter abuts against a limiting stop 152 extending outwardly from the end frame 36, whereupon the counting unit 48 will be reset to the zero position indicated.

When this occurs, further rotation of the ratchet will result in the pawl tooth 136 being cammed out of engagement with the ratchet tooth, whereupon the tripping lever will be formed back to its normal position and pivot the pawl to the position indicated by the dotted lines in Fig. 6. The parts will remain in this position until the drive shaft is again shifted to produce reverse operation of the counters. When this shifting occurs, the pawl being carried laterally simultaneously therewith will be moved out of engagement with the tripping lever 142 as it moves into alignment with the space between the tripping levers, whereupon the spring 138 will pivot the pawl to again lock the ratchet and gear for unitary rotation. When the drive shaft has been shifted laterally to its full extent, the upper arm of the pawl 140 will lie rearwardly of the tripping lever 144 until a resetting operation starts. To prevent any reverse movement of ratchet 124, there may be formed integral with the hub a gear 125 having suitable teeth 127 engageable with a non-back-up pawl 129 normally pivoted into engagement therewith by a spring 131.

It is necessary, of course, that upon operation of the resetting means the counting unit connected for counting operation be disconnected from the reset shaft, whereas the other counting unit be adapted to be connected thereto. To accomplish this, means are provided which are simultaneously operable upon lateral shifting of the reset shaft to connect or disconnect the proper counting unit thereto or therefrom. In the embodiment illustrated, the counting unit 50 is shown just as it has reached zero position and the means are resetting are shown just before they become disconnected from the drive shaft and the unit wheels thereof still being

connected to the reset shaft. To connect the order wheels of each counting unit to the reset shaft, there is pivoted on one of the transverse arms 86 of each wheel a reset pawl 154 having its free end normally spring pressed into a slot 156 provided in the hub 80 (see Fig. 9).

Arranged on the reset shaft are a plurality of longitudinally extending aligned grooves 158 of such length that when in the position shown the reset pawls 154 of the order wheels of the counting unit 50 will be engageable therein when aligned therewith; whereas the reset pawls of the order wheels of the counting unit 48 will ride upon the ungrooved periphery of the reset shaft and thus be freely rotatable thereon. As clearly seen in Fig. 2, the grooves 158 are of such length that when the reset shaft 32 is shifted laterally the grooves will be moved out of alignment with the reset pawls of the wheels of the counting unit 50 and into alignment with the reset pawls of the wheels of the counting unit 48. Obviously the groove 158 for the end wheels of the respective counters is of such length that when in one position the wheel is adapted to be engaged and when in another it is out of alignment therewith. With this arrangement, upon rotation of the reset shaft it will function in the usual manner—that is, upon the groove 158 coming into alignment with the slot 156 the reset pawl 154 will be urged therein and the wheels will be progressively picked up by the reset shaft for simultaneous rotation therewith to zero position. During this operation, the drive pawls 84 will simply ride over the teeth of the driving ratchet 82.

The simultaneous and alternate connecting and disconnecting of the counting units to the drive and reset means is accomplished through the lateral shifting of the yoke 43 whereby the drive shaft and reset shaft are laterally shifted as a unit. This lateral shifting is accomplished by providing the connecting link 42 of the yoke with an elongated slot 160 having its longer axis in a vertical plane. Extending into the slot 160 is an eccentric 162 carried by a ratchet 164; the latter having thereon a pair of peripheral drive teeth 166 and 168 advanced one hundred and eighty degrees from one another. The ratchet 164 has a reduced hub 170 spacing it from a supporting plate 172 extending laterally from the end frame 34. The hub 170 of the ratchet has extending inwardly therefrom a reduced stud 174 pivotally mounted in a suitable opening in the end plate 172.

Actuation of the ratchet 164 is accomplished through oscillation of a gear 176 pivoted on the ratchet hub 170 and having integral therewith outwardly extending, diametrically disposed pawl carrying arms 178. Pivotally mounted in each arm is a pawl 180 normally urged by an associated spring 182 into engagement with the periphery of the ratchet 164 to engage the ratchet teeth 166 and 168 when the gear is operated in a clockwise direction and to rotate relative thereto when the gear is operated in a counterclockwise direction; the gear and ratchet thus in effect constituting a one-way clutch connection, making a positive drive only when operated in one direction.

To oscillate the gear 176 and thus shift the drive and reset connections, there is provided an operating lever 184 pivotally mounted intermediate of its ends on a stud 188 mounted on a supporting plate 172. The inner end of the lever 184 terminates in a gear segment 186 meshing

with the gear 176, and its outer end extends through the slot 27 provided in the side wall of the casing and between the spaced apart supporting hooks 24 of the nozzle supporting bracket 26. The outer end of the lever 184 is further provided with a notch 190 adapted to receive the transverse pin 22 of the nozzle of the dispensing hose 18, and thus upon removal of the nozzle from the bracket the lever 184 will be pivoted about the stud 188. Upon movement of the nozzle from the bracket, the gear segment 186 of the lever will be moved downwardly to oscillate gear 176 in a clockwise direction through one hundred and eighty degrees.

Due to the engagement of the ratchet teeth 166 and 168 with the ratchet pawls 180, the ratchet will be simultaneously rotated through one hundred and eighty degrees, and the eccentric arm 162 will shift link 42 to the right, thus shifting yoke 43 to reverse the drive and resetting connections. Upon replacing the nozzle handle on its supporting bracket, the pin 22 will be received within the notch 190 of the operating lever 184, whereupon the latter will again be pivoted about its axis to move the gear segment 186 upwardly. During the upward movement, the gear 176 will again be oscillated one hundred and eighty degrees, but in a counterclockwise direction, whereupon the drive pawls 180 thereof will merely ride over the periphery of the ratchet until they are again in alignment with the drive teeth 166. As no other movement results, the counting counter will continue to display the amount dispensed or the cost thereof until the next dispensing operation. To facilitate the movement of lever 184 about its pivot, there may further be provided a spring 192 having its upper end connected to the lever and its lower end to the supporting plate 172.

As the two counting units are in axial alignment, a shroud 193 is provided and adapted to be simultaneously shifted upon alternating the drive and reset connections to shroud the counter being reset. The shrouding means consists of a shutter 194 having a forward wall 196 in which there is arranged a plurality of top and bottom openings so disposed that the top openings are in alignment with the unit wheels of the counter 48 and the lower openings in alignment with the unit wheels of the counter 50. Extending rearwardly from each end of the front wall are a pair of arms 198 and 200 pivotally mounted, but freely rotatable, on the reset shaft 32. The arm 200 further has pivotally mounted thereon an upwardly extending link 201 pivotally connected at its upper end to the inner end of a link 202; the outer end of the link being secured to a pivot pin 204 rotatably mounted in a supporting bracket 206 extending outwardly from the end frame 34.

Connected to the opposite end of the pivot pin 204 is a link 208 arranged at substantially right angles to the link 202. The link 208 has cut therein a vertically arranged, elongated slot 210 through which there extends a pin 212 secured to and extending forwardly from the yoke link 42.

As indicated in the drawings, the shroud 193 is positioned so that the numerals of the order wheels of the counting unit 48, which is being operated in a counting direction, are visible; whereas the order wheels of the counting unit 50 are shrouded; it being understood, of course, that the front plate of the casing would have a slot in alignment with the displayed numerals. Obviously, upon shifting of the yoke 43 to the

right to alternate the drive and reset connections, the pin 212 will move in the slot 210 of the link 208, pivoting the link clockwise, as viewed in Fig. 1; whereupon link 202 will simultaneously move in a clockwise direction to lift lever 201 and pivot the shroud upwardly to align the lower set of openings with the order wheels of the counting unit 50 and shroud the order wheels of the counting unit 48.

10 The foregoing structure thus affords in one compact unit a counter including a plurality of counting units and means adapted upon a single operation to automatically connect one counting unit to drive means for a counting operation and the other counting unit to reset means for resetting operation simultaneously with the shifting of shroud means to permit visual indication only of the counting counter. Furthermore, the control means is so arranged that the shifting thereof will automatically occur upon the removal and replacing of the dispensing nozzle, and thus no manual operation other than that required for the dispensing of the liquid is necessary to assure that the counter is properly set and counting from zero upon the commencement of the dispensing of the liquid.

20 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

30 It is also to be understood that the language used in the following claims is intended to cover all of the generic and specific features of the invention herein described and all statements of the scope of the invention which, as a matter of language, might be said to fall therebetween.

40 I claim as my invention:

1. In a counter, a drive shaft, a reset shaft, a pair of counting units mounted on said reset shaft, drive means for said counting units, each including a clutching member, a cooperating clutching member carried by said drive shaft, means for operating said reset shaft in a resetting direction, cooperative means carried by said counting units and said resetting shaft for connecting said units to said reset shaft, and means for simultaneously shifting said drive shaft and said reset shaft to clutch one of said units to said drive shaft for counting operation and to engage the other unit with the reset shaft for resetting operation.

50 2. In a counter, a drive shaft, a reset shaft, a pair of counting units mounted on said reset shaft, means for transferring the rotation of said drive shaft to said counting units to operate same in a counting direction, means for connecting said drive shaft to said reset shaft to operate said units in a resetting direction, and means for disconnecting said reset shaft after one complete revolution thereof.

60 3. In a counter, a drive shaft, a reset shaft means supporting said shaft for lateral movement, means interconnecting the ends of said shafts for simultaneous lateral movement, a pair of counting units mounted on said reset shaft, a pair of clutch means carried on said drive shaft, means for shifting said clutches to alternately connect same, one to a unit to be operated in a counting direction and the other to a unit to be reset.

70 4. In a counter, a drive shaft and a reset shaft,

means supporting said shafts for lateral movement, means for simultaneously shifting said shafts laterally, a pair of counting units mounted on said reset shaft, clutching means mounted on said drive shaft and adapted upon lateral shifting thereof to alternately connect one of said counting units thereto for counting operation, and cooperating means carried by said counting units and said reset shaft operable upon lateral movement of the shafts to alternately connect the other of said units thereto for a resetting operation.

5. In a counter, a pair of counting units, drive means and reset means for said counting units, shifting means for alternately and simultaneously connecting one of said units to said drive means and the other of said units to said reset means, an operating lever for operating said last-mentioned means, and one-way clutch means connecting said lever to said last-mentioned means whereby operation of the lever in one direction operates said means and operation in the opposite direction resets said lever to initial position.

6. In a counter, a pair of counting units, drive means and reset means for said counting units, shifting means for alternately and simultaneously connecting one of said units to said drive means and the other of said units to said reset means, an operating lever for operating said shifting means, and a one-way clutch connecting said lever to said shifting means whereby operation of the lever in one direction operates said shifting means and operation of the lever in the opposite direction resets same to initial position.

7. In a counter, a drive shaft, a reset shaft, a counting unit mounted on said reset shaft, cooperating means carried by said unit and said reset shaft for resetting said units to zero position, a driving connection between said drive shaft and said reset shaft, and means for automatically breaking said drive connection upon the completion of one revolution of the reset shaft.

8. In a counter, a drive shaft, a reset shaft, link arms interconnecting the ends of said shafts, means supporting said shafts for lateral shifting movement, a clutch member fixed on said drive shaft, a pair of transfer gears freely rotatable on said drive shaft and having cooperating clutching faces adapted upon alternate movement of said clutch member to be connected to said drive shaft for rotation therewith, a pair of counting units mounted on said reset shaft, a drive gear for each of said units in constant mesh with each of said transfer gears, a driving connection between said drive shaft and said reset shaft, a second clutch member carried by said drive shaft for connecting said drive member to said drive shaft for simultaneous rotation there-

with, cooperating reset means carried by said counting units and said reset shaft for resetting said units upon rotation of said reset shaft, and means associated with one of said shaft connecting links for shifting said shafts laterally whereby one of said counting units will be connected to the drive shaft for counting operation and the other to the reset shaft for resetting operation.

9. In a counter, a pair of counting units, drive means, means for alternately connecting one of said units to said drive means for counting operation and the other unit to said drive means for resetting operation, and means for disconnecting said unit being reset upon its reaching zero position.

10. In a counter, drive means, a pair of counting units, means for connecting said drive means to said counting unit to operate same in a counting direction, means for connecting said drive means to said units to operate said units in a reset direction, and means for altering said connecting means whereby when one unit is connected to said drive means for counting operation the other unit is connected for reset operation.

11. In a counter, a pair of counting units, drive means, resetting means, and means for simultaneously connecting one unit to said drive means for counting operation and the other unit to said resetting means for resetting operation, and means for disconnecting said unit being reset from the resetting means upon the unit reaching zero position.

12. In a counter a pair of counting units, drive means, a clutch connecting said drive means to one of said counting units, resetting means, a second clutch connecting said resetting means to the other of said counting units, means for simultaneously operating said drive means and said resetting means whereby one of said counting units will operate in a counting direction as the other counting unit is being reset and means for shifting said clutch means to reverse the connection between said drive means, resetting means, and counting units.

13. In a counter, a pair of counting units, drive means, a clutch connecting said drive means to one of said counting units, resetting means, a second clutch connecting said resetting means to the other of said counting units, means for simultaneously operating said drive means and said resetting means whereby one of said counting units will operate in a counting direction as the other counting unit is being reset, means for shifting said clutch means to reverse the connection between said drive means, resetting means, and counting units, shrouding means, and means simultaneously operable with said clutch shifting means to shift said shrouding means to shroud the counting unit being reset.

HARVEY L. SPAUNBURG.
